UNITED STATES PATENT OFFICE.

GEORGE P. WARD, OF CHICAGO, ILLINOIS, ASSIGNOR OF ONE-HALF TO CHESTER L. BUFFINGTON, OF LA GRANGE, ILLINOIS.

MEANS FOR PROMOTING COMBUSTION OF FUEL.

1,251,146.

Specification of Letters Patent.

Patented Dec. 25, 1917.

Application filed October 16, 1916. Serial No. 125,782.

To all whom it may concern:

Be it known that I, GEORGE P. WARD, a citizen of the United States, residing at Chicago, in the county of Cook and State of Illinois, have invented certain new and useful Improvements in Means for Promoting Combustion of Fuel, of which the following is a specification.

My invention relates to a method of improving and promoting the combustion of fuel and especially coal screenings, or other more or less finely divided particles of fuel, and to structures for carrying my invention into effect.

Some of the general objects of my invention are to increase the capacity of furnaces of given dimensions by the production of more rapid and effective consumption of the fuel; varying the speed of the fuel on the grate as the fuel passes through the furnace, and condensing the fuel bed as the volume of the more or less solid combustible material therein is decreased by distillation and combustion, thereby maintaining the particles thereof compacted, to a degree, to prevent excessive quantities of air from passing through the fuel bed, at all times during its progress.

Other and further objects of my invention will become readily apparent to persons skilled in the art, from a consideration of the following description when taken in conjunction with the drawings, wherein:—

Figure 1 is a sectional elevation of my improved furnace and stoker, as applied to a water tube boiler, by means of which my improved method of promoting combustion may be carried into effect.

Fig. 2 is a transverse section, taken on line 2—2 of Fig. 1.

Fig. 3 is a front elevation of the stoker, with parts broken away, showing other parts in section.

Fig. 4 is an enlarged broken away, longitudinal section through one of the coal-moving screw-threaded shafts or grate members.

Fig. 5 is a transverse section, taken on line 5—5 of Fig. 4.

Fig. 6 is a transverse section, taken on line 6—6 of Fig. 4.

Fig. 7 is a modification.

In all the views the same reference characters are employed to indicate similar parts.

In the process of combustion of coal, or other similar fuel, as it is fed forward into a furnace, on the well known chain grate stoker, for example, the fuel is delivered from a hopper or other suitable source of supply, upon the front portion of the moving grate, in a mass which uniformly covers the grate to a depth of several inches. Through this mass, or bed of coal, sufficient air will pass from below to properly meet the requirements of combustion. As the coal, in this example, is fed into the furnace, it first undergoes a coking process, the occluded gases therefrom being ignited and burned as they are drawn over the incandescent bed toward the point of greatest combustion, near the rear of the furnace. The evolved gases have caused a reduction in volume of the more solid fuel matter, leaving more and larger voids which will admit a greater and excessive supply of air, for combustion of the resulting coke. As combustion proceeds, in the progressively moving fuel, larger voids are left, as the volume of solid matter decreases, until the excess of air thus admitted, as a result of the changed condition of the fuel, is so great as to produce a chilling effect to the efficiency detriment of the stoker.

In the chosen embodiment of my improved stoker, the fuel is fed forward thereon into the furnace at a progressively decreasing speed by means that condenses or compacts the deposit and maintains the bed of solid fuel in substantially uniform density, or at any desired variation therefrom, as best adapted for the coal being consumed, whereby to admit only the necessary air, in quantities best adapted for complete combustion, at all the stages in the progress of the coal on the grate.

In the embodiment which I have chosen for the purpose of disclosing my invention 10 and 10' are the furnace side walls or parts of the boiler setting for the water tube boiler 11 in connection with which it is shown. 12 is the front wall of the furnace, which contains on its surface, which confronts the fire, a veneer or coating 14 of

fire brick, or the like, which is more or less refractory to the intense heat produced in the furnace. 13 is the front end of the boiler. 15 is a wall at the rear end of the 5 furnace, having a refractory coating 16 over that portion which overlies or approaches nearest to the stoker grate.

A baffle roof 17, supported by the lower row of water tubes 18, constricts the passage way between the said plate and the wall 12 to provide a throat for the passage 10 of the hot products of combustion arising from the furnace.

Channel beams 19—19' and 20—20' extend 15 the full length of the furnace to support the wall and the refractory projections 21—21' and to support the metallic structure of the furnace. These channel beams are preferably secured together, back to back, so that the lower beam has its flanges 20 projecting outwardly while the inner one has its flanges projecting inwardly for better engagement with the masonry and metal parts of the structure. These beams are 25 downwardly inclined from a true horizontal plane, corresponding with the operative surface of the furnace grate shown in Fig. 1. To the respective beams 19—19' are connected spaced-apart furnace structure cross 30 beams that extend transversely across the furnace and which are indicated by the designating numerals 22 to 27 inclusive. These beams afford support for the rotary grate bar members to which reference will hereafter 35 be more particularly made.

The fuel supporting grate structure is comprised of a series of rotatable, composite, screw threaded shafts of which there are two series, 30 and 31, alternately disposed. One of the series is rotated in clockwise direction, the other series is rotated in the opposite or anti-clockwise direction. Each rotary shaft, of the grate structure, is composed of a plurality of worm or screw 45 threaded sections. In the structure shown, there are five worm sections, of gradually decreasing pitch, that is to say, the worm section 32 has a greater pitch than the adjacent section 33 and will move the fuel bed 50 farther for each revolution of the grate shaft, and in like manner the section 33 has a greater pitch than the section 34, and the pitch of the section 35 is greater than that of the section 36. These worm sections are 55 hollow and are secured together at their ends upon rotatable thimbles 37, provided with notches 38, that engage lugs 39 on each of the worm sections. The threads of these sections, on adjacent shafts, are reversed, 60 that is to say, the threads of all of the sections on one shaft will be right handed while those on the shaft adjacent will be left handed, so that the threads of one section will fit into the interdental space of the 65 worm of the adjacent section, as clearly

shown in Fig. 5. By this means there will be no axial movement of any worms when the shafts are coincidentally rotated in opposite directions. In constructing the grate it is best to permit some material space 70 between the parallel worm sections, of adjacent shafts, in order to provide air spaces through which air may pass, into the bed of superposed fuel from the air chamber below.

The respective connecting sleeves 37 are supported upon the cross beams 22 to 27 inclusive, so as to permit easy rotation of the composite screw shafts. They are held 75 in place on the respective beams by brackets 40 secured to the beams, as by screws 41.

A supplementary cross beam or plate 42 is secured to the channel beams 19—19' at its respective ends, and provides a bearing 80 for each of the parallel rotatable fuel-moving shafts 30 and 31.

An elongated sleeve 43 passes through the bearing afforded by the beam 22, and through the bearing provided by the beam 42, and is connected to the first section 32 90 of the rotating threaded shaft grate members. Each of these elongated sleeves 43, carries a geared pinion 44 which is secured to its respective composite shafts and is of such size as to inter-mesh with a similar 95 pinion carried by the adjacent shaft, as shown in Fig. 3. Certain of the sleeves 43 also carry a worm-wheel 45 that meshes with and is driven by a worm 46 which may be carried upon a driving shaft 47. If a worm wheel and worm be used for each composite 100 shaft the use of the intermediate pinions 44 may be dispensed with, but it is evident that a less number of worms and worm wheels may be employed when the intermeshing 105 pinions are used. For instance, a worm and worm wheel for every alternative shaft would be quite sufficient and the geared pinions could be relied upon for the purpose 110 of transmitting power from one composite shaft to the other. The shaft 47 is supported upon brackets 48, that are placed, at suitable intervals, upon the beam 42. The shaft 47 may be rotated by any suitable means, such as a small steam engine, electric motor, 115 or the like. At the ends of the structure 42, where two of the shafts are located at higher altitudes than those composing the major portion of the grate, an intermediate gear wheel 49 may be employed for transmitting 120 the motion to the geared pinion 50, as the pinion 51 and the shaft upon which it is located is not rotated by a worm and gear drive, as are the remaining composite shafts 125 of the series.

In order to prevent the rotary shafts from becoming warped by the effect of the intense heat to which they are each subjected, and thereby being distorted out of alignment, so 130 that it would be difficult to rotate them, I

cool these grate members by circulation therethrough of a cooling medium throughout their length. To this end the last coupling sleeve 37' in the series, of each shaft 5 is closed at its end, as at 52, and I extend a pipe, or tube 53, into each of the composite shafts to a point near the closed end 52 of the sleeve 37', as clearly shown in Fig. 7. A circulating cooling medium is passed 10 through the interior pipe 53 until it reaches a point near the end of the structure where it passes out into the annular space provided by the interior of the composite section 32 to 36 inclusive, and through the coupling sleeves 37. The circulating medium may be water, in which event, it is heated by the heat extracted from the grate members by passing through these fuel feeding shafts constituting the grate of the structure, and 15 its temperature being raised to a considerable extent by this means, it may be pumped into a heater and subsequently passed into the boiler, thereby conserving the heat that is taken away from the grate and adding 20 efficiency to the service. In the particular exemplification there is no means shown for carrying the water away after it passes out through the elongated tubes 43 in the end of each of the rotary shafts, but any sort of a 25 trough or conduit may be employed for the purpose. In the event that air be used for the purpose of cooling the grate members, such a conduit will be unnecessary, as the heated air will escape from the front end of 30 the structure into the surrounding atmosphere.

For introducing the cooling fluid medium into the tube 53 I provide a header 55 and branch connections 56 therefrom into the 40 respective tubes 53.

Pipes 57 communicate with a suitable source of air supply and are connected with the head 55. There is one shown at each end, for securing a more equable distribution 45 of the cooling medium, each of which is controlled by a valve 58. The pipes 57 are connected to a breeching or head 59, which is at all times filled with air, under pressure, at a few ounces, or to whatever extent is necessary or desirable for producing the required 50 forced or blast draft that may be employed in connection with my system. The breeching 59 communicates with a closed casing 60 by a pipe 61, of which there is preferably 55 one at each side of the furnace. The casing 60 is located below the furnace and communicates with a chamber 62 included within a closed casing 63, through regulable dampers or valves 64, 65, 66 and 67. The chamber 62 60 is divided into sub-chambers 68, 69, 70 and 71, each sub-chamber being provided with a corresponding regulable air inlet. These chambers are divided by plates 72, 73, 74, 75 and 76, there being a plate immediately 65 below each of the cross beams 23 to 27 in-

clusive, and there being one sub-chamber for each worm section of the rotatable grate members.

The base walls of the casing 63 are inclined, so as to cause any siftings or ashes that may fall from the grate, to gravitate toward the transverse center of the casing. The inclined walls of the casing 63 are connected in the substantial transverse center of the casing by a pipe 77 having independent ports 78 into each of the sub-chambers 68 to 71, inclusive, as shown in Fig. 1. Another pipe 79 fits closely in the pipe 77 and may be rotated therein, by means of a crank arm 80. The pipe 79 is provided with circumferentially spaced-apart ports 81 that are adapted to register with the respective ports in the sub-chambers 68 to 71, respectively, with the opening 78 provided in the outer or larger pipe. The ports 81 are not in the same radial or longitudinal planes so that the pipe 79 may be rotated to different degrees to bring either of the ports 81 into register with the respective port 78 in either of the chambers 68 to 71, respectively. The pipe 90 79 is provided with one long port, however, which is of sufficient linear extent to include registration with all of the ports 78, in all of the sub-chambers 68 to 71, so that when the pipe 79 is turned so as to bring the long 95 port into register with the ports of the respective sub-chambers, communication is thereby made between all of the sub-chambers and the interior of the pipe 79. The pipe 79 enters the three way valve fitting 100 82 containing a three-way valve 83, and communicating with the vertically extending pipe 84, which, near the top end, is bent forwardly, as at 85. By operation of the three-way valve, the pipe 79 may communicate 105 with a pipe 86 that is in connection with an ash receiving receptacle outside of the furnace.

A chamber 88 is provided between the plate 72 and the plate 89 for communication with the space 90 immediately under the segments 32 of the rotatable grate members. A plate 91 is placed under the segments 32 for movement of the siftings from under the segments into the chamber 88. The pipe 79 also has ports communicating 115 with the chamber 88 substantially as heretofore described with reference to the larger chambers. The pipe 79 may be rotated, by means of a crank arm 80, a connecting 120 mechanism 92 and the lever 93.

94 is a beam substantially on a level with the floor surface of the boiler room and which carries brackets 95 and 96 for support of the shaft 97 that is rotatable by the lever 93 in the act of rotating the valve pipe 79. Each of the air-admitting registers, 64 to 67 inclusive, is carried upon an individual shaft 98, which extends transversely through the respective chambers 68 130

to 71 and carries on one end a register disk 99 having openings, or ports corresponding with the ports made in the wall of the casting 63 and it carries on the other end a 5 compression spring 100 held in place by a nut 101 in order to hold the rotatable register or valve disk 99 in close and intimate contact with the vertical walls of the casing.

10 Secured to each of the shafts 98 is an arm 103, for the purpose of rotating the register valve 99. This arm is connected to a rod 104 which extends forwardly and is connected to a bell crank lever 105. The 15 lever is provided with a hand piece 106 and a latch 107 that is spring pressed, as by a spring 108, in contact with a ratchet quadrant 109 so as to hold the lever in adjusted position for the purpose of opening and 20 closing the respective registers to the extent desired. Secured to the cross beams 22 and 23 are bearing brackets 109 and an intermediately disposed bracket 110. These brackets support the transversely extending 25 shaft 111. Each of the levers 105 is loose on the shaft 111, the segments 109 being secured thereto, as by screws or bolts 112, except the segment 113, which is a master segment, and is fixed to the bracket 30 110, as at 114, and a lever 113^a, of this segment is secured to the shaft 111, as at 115. Now from the foregoing description it is manifest that the amount of air passing 35 from the chamber 60 into any one of the sub-chambers 68 to 71 inclusive, may be independently regulated, by the dampers or registers heretofore described, by the manipulation of the respective hand lever 106. After each of the registers 64 to 67 including 40 have been independently set to permit the proportionate quantity of air to pass into the sub-chambers 68 to 71 inclusive, as desired, the entire number of registers may be simultaneously moved by manipulation 45 of the master hand lever 113^a, with reference to the fixed segment 113, whereby the shaft 111, with all of the segments of the 109 class fixed thereto, is rotated correspondingly to move all of the dampers to 50 the extent desired. By this means the amount of air entering any one of the sub-chambers may be independently regulated and the quantity necessary or required for them collectively may be varied or regulated by the master lever.

A hopper 120 extends across the front of the furnace and is connected with any suitable source of fuel supply. It is provided with an adjustable door 121, supported by a chain 123, upon a segment 124, which turns on the axis of a shaft 125, which also extends across the front of the furnace, and which may be rotated to raise the door 121 to the extent desired to regulate 60 the thickness of the deposit or bed of

coal emplaced upon the rotatable members 30, 31, of the grate.

In Fig. 7 I have shown a modification of the structure shown in Fig. 1, wherein a perforate sifting plate 126, is placed immediately below and parallel with the screw-threaded segments of the grate in the respective sub-chambers. This plate is perforated, as at 127, to permit air, to pass from the respective sub-chamber to the 75 grate members, necessary for supplying oxygen to the burning fuel deposited thereon. The plates are intended to support any loose or finely divided coal, or other fuel that may pass down between the adjacent 80 screw threaded members and is adapted to hold such coal, or other finely divided fuel, in close proximity with the screw members, so that in the rotation of the screw threaded members the coal, or such fuel as may rest 85 upon the sifting plate 126, will be moved forwardly on the plate by means of the threaded screw and pushed up through the aperture 128, which is provided by making the screw member shorter than is shown in 90 the structure illustrated in Fig. 1. By this means the siftings that rest upon the plate 126, will, by the operation of the screw, be forced up through the aperture 128 into or above the original altitude and be carried 95 on by the next adjacent screw threaded segment, of the rotating grate member to be consumed in its futher progress.

The operation of the device, briefly, is as follows: The parallel screw threaded grate members, 30—31, are constantly rotated by the means heretofore described, adjacent members being rotated in opposite directions. The deposit of coal on the first segment 32 of the grate members is regulated by 100 the height at which the door 121 is raised above the general surface of the grate structure. The coal, or other similar fuel is moved forwardly by the threads upon the 105 rotative grate members and as it passes into the furnace begins to coke. By the time the bed of fuel has been thus moved by the rotation of, and along the screw threaded members, from the segment 32 to the segment 33, the volume or quantity of solid 110 matter has, to some extent, been decreased by the coking process. The screw threaded members 33 are of less pitch than the threaded members 32 and therefore the bed of coal 115 will be passed along by these members at a relatively slower speed and therefore the particles of the bed will be compacted by the difference in speed of the two members, closing up the excessive air spaces between the particles of fuel resulting from the decrease 120 in volume, due to combustion. When the bed has reached the segments 34, which are of less pitch than the segments 33, the progress of the coal will be at a further reduced speed-rate, and further compression or com- 125 130

pacting of the fuel will be effectuated by the difference in the pitch of the segments 33 and 34, again compensating for the loss of solid matter, due to the effect of combustion. 5 This action is repeated when the fuel passes on the segments 35 and again repeated when it passes on to the segments 36. As this time the coal is reduced substantially to ash or cinders and it is thrown off at the final end 10 of the segments 36 into a space at the rear of the furnace, from which it may be conveyed by any suitable means, to a more accessible location. The extent to which the bed may be compacted is determined by the 15 difference in pitch of adjacent screw sections.

It will be observed from the foregoing description that the progress of the coal through the furnace is constantly undergoing 20 a varying speed rate, being moved slower, substantially in proportion as the solid matter is consumed.

In the progress of the coal, should any combustible matter fall through the rotat- 25 ing grate members into the chambers 68, 69, 70 or 71, it will finally reach the port 78, in the outer pipe in the casing 63, and when the inner pipe 79 is rotated, so as to cause the valve therein to register with the restricted 30 port the combustible material will pass through the inner pipe 79 through the three way valve 80 and through the vertical in-turned pipe 84 and be blown by the air pres- 35 sure, which is within the respective chambers 68 and 71 inclusive, into the incandescent coal or the hot gases therefrom, within the furnace.

The amount of combustible material will decrease progressively from the chamber 30 40 68 to the chamber 71. The chamber 71 will contain largely ash and when it is desired to remove the ash from the chamber 71, the three-way valve may be rotated, so that it will communicate with the pipe 86, then the 45 pipe 79 should be rotated so that the valve 81 will communicate with the valve 78 of the chamber 71, whereby the air pressure, within the chamber 71, will cause the ash to be blown out into a space beyond the furnace, 50 from which it may be subsequently conveyed, by any suitable means.

While I have herein shown a single embodiment of my invention for the purpose of clear disclosure it is manifest that many 55 changes in the general arrangement, disposition and configuration of the parts may be made within the scope and intendment of the appended claims.

Having described my invention, what I 60 claim is:—

1. In a furnace, a series of parallel, rotatable grate-members, bearing fuel-moving worms, the pitch whereof progressively decreases toward the rear of the furnace.

65 2. In a furnace, a series of parallel, rota-

table grate-members, each bearing, respectively, right and left hand intermeshing worm-members, the pitch of which decreases progressively with the movement of the fuel thereon. 70

3. In a furnace, a series of parallel, rotatable, hollow grate-members bearing, respectively, right and left hand, intermeshing worm members, the pitch of which decreases progressively with the movement 75 of the fuel thereon and means to pass a cooling medium through said members.

4. In a furnace, a series of parallel, rotatable, hollow grate-members bearing, respectively, intermeshing, sectional worm 80 members, the pitch of the respective sections decreasing progressively with the movement of the fuel thereon and means for passing a cooling medium through said members.

5. In a furnace, a series of composite, 85 parallel hollow grate-members, adjacent members rotatable in opposite directions, a series of alternate members each composed of right-hand worm-sections intermeshing with a series composed of left-hand worm-sections, said sections decreasing in pitch, progressively from front to rear of the grate and connections between said grate members, whereby to rotate them. 90

6. In a furnace, a series of parallel, rotatable grate members, each composed of worm-sections of varying pitch arranged with sections of greatest pitch to receive the fuel and progressively decreasing in pitch toward the rear end of the grate, adjacent 95 grate members being rotatable in opposite directions and bearing right and left hand worm-sections, respectively; an air-proof casing under each section and regulable means for admitting air under pressure into 100 105 said sections.

7. In a furnace, a series of parallel, rotatable grate members, each composed of worm-sections of varying pitch arranged with sections of greatest pitch to receive the 110 fuel and progressively decreasing in pitch toward the rear end of the grate, adjacent grate members being rotatable in opposite direction and bearing right and left hand worm-sections, respectively, an air-proof 115 casing under each section and independently regulable means for admitting air under pressure into each said casing.

8. In a furnace, a series of parallel, rotatable, hollow grate-members each composed of worm-sections of varying pitch, arranged with sections of greatest pitch to receive the fuel and progressively decreasing in pitch toward the rear end of the grate, adjacent 120 grate members being rotatable in opposite directions and bearing right and left hand worm-sections, respectively; an air-proof casing under each section; independently 125 regulable means for admitting air under pressure into each said casing; a pipe ex- 130

tending through each grate member to convey a cooling medium under pressure through each said member to permit the medium to return to the end at which it was introduced and a header for all said pipes.

In testimony whereof I hereunto set my

hand in the presence of two subscribing witnesses.

GEORGE P. WARD.
